Nathan W. Crandall
Atty.

UNITED STATES PATENT OFFICE.

CHARLES A. KING, OF MERIDEN, CONNECTICUT.

STORAGE-TANK FOR LIQUID FUEL.

SPECIFICATION forming part of Letters Patent No. 471,615, dated March 29, 1892.

Application filed May 16, 1891. Serial No. 893,061. (No model.)

To all whom it may concern:

Be it known that I, CHARLES A. KING, a citizen of the United States, residing at Meriden, in the county of New Haven and State of Connecticut, have invented certain new and useful Improvements in Storage-Tanks for Liquid Fuel; and I do declare the following to be a full, clear, and exact description of the invention, such as will enable others skilled in

10 the art to which it appertains to make and use the same, reference being had to the accompanying drawings, and to the letters and figures of reference marked thereon, which form a part of this specification, and represent, in—

15 Figure 1, a side elevation of a tank fitted with my appliances in a manner well calculated to illustrate the spirit of my invention. Fig. 2 is a front elevation of the same device. Fig. 3 is a detail view in section of the relief-valve and protecting-hood. Fig. 4 is a transverse section of the flame-arrester located beneath the relief-valve and is taken through the line X of Fig. 1.

20 This invention relates to improvements in storage-tanks for liquid fuel; and it consists in certain automatic appliances, the details of construction and arrangement of which will be more fully hereinafter specified, and pointed out in the claims.

25 The object of this invention is to provide means for automatically confining the liquid within the tank in case of fire; also, to permit of the free inlet of air and outlet of vapor or gas when required.

30 This device is more particularly designed for storing liquid-fuel oils, but, as will be readily comprehended, is well adapted to the storage of any volatile liquid or in any case where it is desirable to prevent a circulation 35 within the tank and reduce evaporation.

35 Heretofore tanks of this description have been allowed unrestricted circulation, which in warm weather results in a high degree of evaporation. The vapor arising therefrom, 40 being unrestrained, rises upward in an approximately perpendicular line, and, mingling with the atmosphere, forms a column of highly-explosive compound extending from the outlet of the tank some distance upward, and beyond which extends a column of cold damp atmosphere, which respectively form a priming or magazine to the tank and an excellent

electric conductor by which during a thunder or electric storm lightning is attracted and, traversing the same in a downward direction, 55 ignites the combustible vapor, having thereby in the manner described caused numberless terrific explosions and disastrous fires. All of the above-cited objections in and defects of storage-tanks are obviated and removed and absolute safety insured by the use of the automatic relief-valve, which forms an important feature of this invention and to which reference in detail will be hereinafter made. Other valuable results are also obtained by tanks of the above description being provided with the automatic arrangement for preventing the escape of liquid and the consequent nursing of fire by the saturation of wood or other combustible material with 70 which it would be liable to contact by reason of the gage-glass becoming broken by excessive heat arising from a conflagration in the immediate vicinity.

Special reference to the means by which the 75 above-mentioned results are accomplished will be hereinafter made in detail.

In the drawings, A represents a tank of ordinary construction; B, the vent or relief-pipe; C, the relief-valve; D, the flame-arrester; E, 80 the bonnet or hood for protecting the relief-valve from the weather.

F is an ordinary gage-glass for the purpose of indicating the height of the liquid in the tank.

85 A' and A² are valves introduced into the gage-glass fittings between the said gage-glass and the tank for the purpose of shutting off the liquid from the gage-glass or to prevent the escape of the contents of the tank in case 90 of the said glass becoming broken by accident. B' and B² are levers or wrenches attached to the valve-stems, through which the said valves are operated.

G is a connecting-rod or pitman for connecting the valve-levers together for the purpose of actuating them simultaneously.

H is a weight attached to the connecting-rod or pitman for the purpose of closing the valves automatically in case of fire.

100 I is a stop or hook, preferably formed integral with the connecting-rod G, and is designed to receive the weight and relieve the valves when closed. A shelf or support may

be provided below the weight and adapted to receive the same, thereby accomplishing the same result.

The dotted lines in Fig. 1 denote the positions assumed by the various parts when the valves are closed.

J is a hook formed integral with the connecting-rod for the purpose of attaching the weight H. A chain or cable may be substituted for the connecting-rod without altering the invention.

I is the safety-hook and is provided with a soft-soldered or fusible joint 4. The upper end of said hook is secured to the top of the tank or other suitable place by the aid of any well-known means of fastening—such as bolts, screws, rivets, &c.—and is designated in the drawings by the figure 7. The lower end of the said hook is provided with a lug or projection 20, for the purpose of engaging with the slot 3 in the rod G, thereby sustaining the weight H and retaining the valves A' and A² in an open position.

The gage-glass is provided with the usual fittings and is connected with the tank in precisely the same manner that they are connected to steam-boilers, which is thought to be too well understood by those skilled in the art to which it appertains to require a detailed description. The valves A' and A² are introduced into the fittings in exactly the same manner as the ordinary stop-cock, and are preferably of the kind known as "straight-way" valves. The relief-valve C communicates with the tank through the pipe B, which is connected in the usual manner. A chamber D is inserted into the relief-pipe between the relief-valve and the tank, and within said chamber are disposed pieces of wire of small diameter running lengthwise of and terminating somewhat below the top of said chamber. The said chamber may be of any desired shape and dimensions, the object of the device being to form a series of small orifices through which the gas or vapor is forced to pass in order to escape from the tank, thereby forming a flame-arrester after the fashion of the well-known miners' safety-lamp. The relief-pipe is designed to be conducted away to a point out of reach of the flames arising from the burning of buildings in the vicinity or otherwise; but in case, from any cause whatever, the escaping gas should become ignited, it would become cooled to that extent in passing through the arrester that the flames would either be extinguished or burn harmlessly at the top, thereby precluding the possibility of the flames passing down the pipe and causing an explosion of the gas within the tank.

The gage-glass F is surrounded with an air-tight shield or jacket N, which is provided with a front of glass or other suitable transparent material N', the object of the shield being to protect the gage-glass, so as to insure the fusing of the joint in the safety-hook before the said glass shall become

broken with the heat, and to otherwise shield it from accidental breakage.

Referring to Fig. 3, the relief-valve is shown in section. Openings T' and T² are formed in the sides of the body of the valve and flaps or lids P' and P² are pivoted or hinged in any preferred manner so as to cover and rest upon the seats K' and K². The lid P' being hinged upon the inside, as will readily be seen, will act as an inlet-valve, and will be raised from its seat during the process of emptying or drawing the liquid from the tank. It is equally as evident that in filling the tank the liquid as it is introduced will condense the air or vapor contained therein until the lid P² is raised from its seat, thereby forming an automatic outlet for the same. It is evident that by loading the outlet-valve any desired pressure may be retained within the tank.

That the construction of the valve may be greatly varied without departing from my invention will be readily seen. Therefore I would not bind myself to any particular construction, but desire to make them in any approved shape.

While it is obvious that the seats may be constructed in an upright position or otherwise, and the flaps or lids held in position by the aid of springs, yet I prefer the construction shown, in which the valve-seats assume an angle, thereby closing the flaps or lids by gravitation. It is also obvious that the same results may be accomplished by constructing an outlet and an inlet valve separately and attaching them to different pipes or tubes; but I prefer the construction shown on account of its compactness. The cut-off arrangement may be operated at any time by simply detaching the hook or lug 20 from the slot 3.

The operation of the cut-off arrangement in case of fire is as follows: When the temperature shall rise to a sufficient degree to melt or fuse the joint 4, the weight H is released by the parting of the safety-hook I and, closing the valves, prevents the escape of the liquid.

Having thus described my invention, what I claim, and desire to secure by Letters Patent, is—

1. The combination, with a storage-tank provided with a gage having an air-tight inclosing-jacket, connections between the ends of the gage and the tank, and a valve in each of said connections and in vertical alignment, of parallel levers attached to the respective valves, a bar coupling the ends of said levers and carrying a weight, said bar being provided with a slot, a two-part rod connected by a fusible joint and provided at its lower end with a hook engaging the slot in the coupling-bar, and adapted to normally retain the latter in elevated position, substantially as and for the purpose set forth.

2. The herein-described storage-tank, consisting of the tank proper, a gage having an air-tight jacket, connections between the ends

of the gage and the tank, a valve in each of said connections and in vertical alignment, parallel levers attached to the respective valves, a bar coupling the ends of the said levers and carrying a weight, a two-part rod connected by a fusible joint, and provided at its lower end with a hook engaging a slot in the bar, a relief-pipe projecting from the tank and provided with inlet and outlet valves,

and a chamber interrupting said pipe and provided with a filling, all arranged substantially as and for the purpose set forth.

In testimony whereof I affix my signature in presence of two witnesses.

CHARLES A. KING.
